INHALER

Samuel Miller, New York, and Arthur C. Emelin, Mamaroneck, N. Y., assignors to Schenley Industries, Inc., New York, N. Y., a corporation of Delaware

Application June 25, 1949, Serial No. 101,292

15 Claims. (Cl. 128—206)

1

This invention relates to inhalers, and relates more particularly to inhalers for use with powdered inhalants.

Various practical difficulties have been encountered in using, in inhalers, powdered inhalants, such as powdered penicillin for example which has come into wide use as a medicament for respiratory ailments. Thus, the hygroscopicity of the powder causes it to agglomerate, forming particles which are too large for effective use. Moreover, prior devices did not admit sufficient air into the inhaler, or admitted air into the inhaler in such a manner as to cause a Venturi effect with the result that the powder was driven into the corners of the inhaler receptacle which holds the powder supply.

It is an important object of this invention to provide a novel inhaler for powdered inhalants which will be free from the foregoing and other disadvantages and which will be simple and inexpensive in construction and efficient in use.

Another object of this invention is the provision of an inhaler which is so constructed as to permit of the most effective utilization of the powder.

Still another object of this invention is the provision in an inhaler of means for shattering any powder agglomerates.

Other objects of this invention, together with certain details of construction and combinations of parts, will appear from the following detailed description and will be pointed out in the appended claims.

In the accompanying drawing wherein a preferred embodiment of our invention is shown:

Fig. 1 is an exploded view of the inhaler of our invention showing the receptacle for the powder below the mouth or nose contact tube.

Fig. 2 is a top plan view looking in the direction of the arrows on line 2—2 in Fig. 1.

Fig. 3 is a vertical cross-sectional view of the inhaler with the contact tube in position within the receptacle, and

Fig. 4 is a horizontal cross-sectional view taken along line 4—4 of Fig. 3.

Like reference numerals indicate like parts throughout the several views of the drawings.

Referring now to the drawings for a detailed description of our invention, the reference numeral 5 indicates a receptacle which is substantially circular in cross-section and which is provided with projections 6 to supply stability to the inhaler when set down, and a reduced portion 7. The outer surface of the reduced portion is provided with screw threads 8 which are employed

2

to keep the closure member, with which the receptacle 5 is originally closed, in position.

Formed in the base on the inside of receptacle 5 is a substantially hemispherical depression 9 adapted to receive a charge of the powdered medicament. A shoulder 11 is formed circumferentially of the depression 9, which shoulder is provided with slots or passageways 12 leading into said depression at a tangent to the periphery thereof. The inner wall of the receptacle is provided with integral ribs or projections 13.

Adapted to be received in receptacle 5, to be seated on shoulder 11 and spaced from the inner wall of said receptacle by ribs 13 is a mouth or nose contact tube 14 of substantially cylindrical form. Spacing of the contact tube from the inner wall of the receptacle forms airways to supply air to the said receptacle.

As is shown at 15 the upper end of said contact tube is conically shaped to facilitate the entrance thereof into a nostril or the mouth and the tip is provided with an opening 16. The barrel of contact tube 14 is provided with an integral helical rib 17, the spiralling of which corresponds with the direction of the air flow which will hereinafter be more fully described.

The inhaler of our invention may be made of any suitable material such as metal, glass ceramics or plastics.

In use, a charge of the powdered medicament is placed in depression 9 of receptacle 5. As suction is applied at opening 16 by the mouth or nose of the user, air is drawn in through the space 18 formed between the outer surface of contact tube 14 and in the inner wall of reduced portion 7 of receptacle 5. This air enters depression 9 through slots 12, thus avoiding any Venturi effect. The air with some of the powder entrapped therein passes from the receptacle to and through the barrel of the contact tube 14. The helical rib in said tube, the spiralling of which, as stated above, corresponds with the direction of the flow of the air towards opening 16, causes the stream of air and powder to follow a tortuous path at a relatively rapid rate with the result that any large particles or agglomerates of powder are broken up or shattered by striking against the several convolutions of the helical rib 17, which convolutions act as baffles.

It will be appreciated that our novel inhalant may be used effectively with inhalants which are not in powdered form, for example, inhalants in the form of a paste or a solid piece.

The embodiment of our invention shown and described herein is to be considered merely as

illustrative, as our invention is susceptible to variation, modification and change within the spirit and scope of the appended claims.

We claim:

1. An inhaler of the class described, comprising a receptacle for holding a supply of inhalant, a plurality of ribs on the inner wall of said receptacle, a contact tube seated in said receptacle and spaced from the inner wall thereof by said ribs whereby airways are formed, and baffling means on the inside of said contact tube positioned to provide a tortuous path for air drawn through said airways into said contact tube.
2. An inhaler of the class described, comprising a receptacle for holding a supply of inhalant, a plurality of ribs on the inner wall of said receptacle, a contact tube seated in said receptacle and spaced from the inner wall thereof by said ribs whereby airways are formed, and a helical rib on the inside of said contact tube.
3. An inhaler of the class described, comprising a receptacle for holding a supply of inhalant, a plurality of ribs on the inner wall of said receptacle, a contact tube seated in said receptacle and spaced from the inner wall thereof by said ribs whereby airways are formed, and a helical rib having a plurality of convolutions on the inside of said contact tube.
4. An inhaler of the class described, comprising a receptacle, a depression in said receptacle for holding a supply of inhalant, a plurality of ribs on the inner wall of said receptacle, a contact tube seated in said receptacle and spaced from the inner wall thereof by said ribs whereby airways are formed, said receptacle having passageways joining said airways and said depression, and baffling means on the inside of said contact tube.
5. An inhaler of the class described, comprising a receptacle, a depression in said receptacle for holding a supply of inhalant, a plurality of ribs on the inner wall of said receptacle, a contact tube seated in said receptacle and spaced from the inner wall thereof by said ribs whereby airways are formed, said receptacle having passageways joining said airways and said depression, and a helical rib on the inside of said contact tube.
6. An inhaler of the class described, comprising a receptacle, a depression in said receptacle for holding a supply of inhalant, a plurality of ribs on the inner wall of said receptacle, a contact tube seated in said receptacle and spaced from the inner wall thereof by said ribs whereby airways are formed, said receptacle having passageways joining said airways and said depression, and a helical rib having a plurality of convolutions on the inside of said contact tube.
7. An inhaler of the class described, comprising a receptacle, a hemispherical depression in said receptacle for holding a supply of inhalant, a plurality of ribs on the inner wall of said receptacle, a contact tube seated in said receptacle and spaced from the inner wall thereof by said ribs whereby airways are formed, said receptacle having slots leading into said depression substantially tangentially to the periphery thereof and joining said airways with said depression, and baffling means integral with the inner wall of said contact tube.
8. An inhaler of the class described, comprising a receptacle, a hemispherical depression in said receptacle for holding a supply of inhalant, a plurality of ribs on the inner wall of said receptacle, a contact tube seated in said receptacle and
9. An inhaler of the class described, comprising a receptacle, a hemispherical depression in said receptacle for holding a supply of inhalant, a plurality of ribs on the inner wall of said receptacle, a contact tube seated in said receptacle and spaced from the inner wall thereof by said ribs whereby airways are formed, said receptacle having slots leading into said depression substantially tangentially to the periphery thereof and joining said airways with said depression, and a helical rib having a plurality of convolutions integral with the inner wall of said contact tube.
10. An inhaler of the class described, comprising a receptacle, a hemispherical depression in said receptacle for holding a supply of inhalant, a shoulder in said receptacle circumferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots joining said airways with said depression, and baffling means on the inside of said contact tube.
11. An inhaler of the class described, comprising a receptacle, a hemispherical depression in said receptacle for holding a supply of inhalant, a shoulder in said receptacle circumferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots joining said airways with said depression, and a helical rib on the inside of said contact tube.
12. An inhaler of the class described, comprising a receptacle, a hemispherical depression in said receptacle for holding a supply of inhalant, a shoulder in said receptacle circumferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots joining said airways with said depression, and a helical rib having a plurality of convolutions on the inside of said contact tube.
13. An inhaler of the class described, comprising a receptacle, a hemispherical depression in said receptacle for holding a supply of inhalant, a shoulder in said receptacle circumferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots leading into said depression substantially tangentially to the periphery thereof and joining said airways with said depression, and baffling means on the inside of said contact tube.
14. An inhaler of the class described, comprising a receptacle, a hemispherical depression in said receptacle for holding a supply of inhalant, a shoulder in said receptacle circum-

ferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots leading into said depression substantially tangentially to the periphery thereof and joining said airways with said depression, and a helical rib on the inside of said contact tube.

15. An inhaler of the class described, comprising a receptacle, a hemispherical depression in said receptacle for holding a supply of inhalant, a shoulder in said receptacle circumferentially of said depression, a plurality of ribs on the inner wall of said receptacle and above said shoulder, a contact tube seated on said shoulder of said receptacle and spaced from the inner wall thereof by said ribs whereby airways are formed, said shoulder having spaced slots leading into said depression substantially tangentially to the periphery thereof and joining said airways with

said depression, and a helical rib having a plurality of convolutions on the inside of said contact rib.
